CLAIM

The ornamental design for a pet weighted blanket as shown and described.

DESCRIPTION

FIG. 1 is a top plan view of the pet weighted blanket; FIG. 2 is a bottom plan view of the invention; FIG. 3 is a front elevation view of the invention, the rear elevation view being a mirror image; and, FIG. 4 is a right end view of the invention, the left end view being a mirror image.

The broken lines depict stitching that is not claimed as part of the design.
